CONCRETE PIPE CASTING APPARATUS

Randell C. Woods, Mecca, Calif.

Application October 30, 1951, Serial No. 253,846

2 Claims. (Cl. 25—126)

1

This invention relates to concrete pipe casting apparatus and more particularly to an outer mould or jacket in which concrete pipe sections are cast.

It is among the objects of the invention to provide an outer mould or jacket for casting concrete pipe sections which jacket is of substantially unitary construction and is not circumferentially expansible to release a cast pipe section therefrom, which includes a unitary, substantially cylindrical shell having no longitudinal cut or opening for expanding the shell and can thus have materially less weight and greater strength than equivalent mould jackets having longitudinal cuts or openings therein for circumferential expansion thereof; which is slightly tapered from end to end to provide sufficient draft for facilitating removal of the jacket longitudinally from a pipe section cast therein and has handles or lugs projecting therefrom for also facilitating removal of the jacket from the pipe section; which is releasably connectible at its larger end to a pallet ring and includes quick release means for freeing it from the pallet ring; and which is simple and durable in construction, economical to manufacture, and adaptable for use with various types of concrete tamping and packing machines.

Other objects and advantages will become apparent from a consideration of the following description and the appended claims in conjunction with the accompanying drawings, wherein:

Figure 1 is a top plan view of a mould jacket illustrative of the invention shown in operative association with a pallet ring and a portion of a concrete tamping machine;

Figure 2 is a side elevational view of the assembly illustrated in Figure 1, a portion of the jacket being broken away and shown in longitudinal cross section to better illustrate the construction thereof; and

Figure 3 is a side elevational view of the assembly rotated 90° from the position illustrated in Figure 2.

With continued reference to the drawings, the numeral 10 designates a cylindrical inner form or core for moulding concrete pipe sections, this core constituting a portion of a concrete tamping machine of a form well known to the art and being mounted at one end on a plate 11 which also constitutes a part of the tamping machine. The core 10 is slightly tapered in a direction away from the base plate 11 to provide draft for facilitating the removal of the core from a concrete pipe section cast thereon.

2

An annular pallet ring 12 is shown supported on the base plate 11 and surrounding the core 10 adjacent the base plate. The pallet ring is also of well known construction, the form illustrated being a form provided to produce tongue formations on the ends of pipe sections for joining pipe sections together in end to end relationship. The pallet rings are made in various other shapes for different purposes and are removable with the casting from the core 10 when the casting is removed from the core, these pallet rings being left in place on the casting until the casting has completely set.

The pallet ring is supported in position on the base plate 11 by suitable supporting blocks 13 and other blocks 14 are provided on the base plate and project upwardly therefrom for centering an outer mould casing or jacket on the base plate so that it surrounds the core 10 and is annularly spaced from the core a uniform distance entirely around the latter.

As the core, the base plate with the mounting and centering blocks and the pallet ring are all well known to the art and constitute no part of the present invention except in the association thereof with the novel mould jacket, a further illustration and description of these elements is considered unnecessary for the purposes of the present disclosure.

The outer mould casing or jacket of the present invention is generally indicated at 15 and comprises a metal tube 16 of cylindrical shape having a length substantially equal to the length of the core 10 and an inside diameter greater than the outside diameter of the core by twice the wall thickness of the concrete pipe section to be cast between the core and the jacket. The tube 16 is preferably formed of a durable material, such as hardened aluminum, and has smooth inner and outer surfaces and is slightly tapered from one end to the other to provide draft for facilitating the removal of the jacket from a concrete pipe section cast therein.

A reinforcing band 17 surrounds the tube 16 at the smaller end of the latter and has an inwardly directed annular flange 18 at one end overlying the adjacent smaller end of the tube, this being the upper end of the tube when the tube is disposed in operative association with the core 10, as is particularly illustrated in Figure 2.

A reinforcing band 19, wider than the band 17 surrounds the larger, bottom end of the tube and reinforcing bands 20 and 21 surround the tube at spaced apart locations between the end bands 17 and 19.

Plates 22 and 23 are secured to the outer surface of the tube 16 substantially at the midlength location of the tube and at diametrically opposed locations therearound with their upper ends adjacent the bottom edge of the reinforcing ring 20 and lugs or handles 24 and 25 project outwardly one from each of these plates substantially radially of the tube 16. In the case of small jackets these handles may be grasped by a hand to facilitate removing the jackets from concrete pipe sections cast therein and in the case of larger jackets these handles or lugs may be engaged by a hoist chain or cable for removing the jackets from the cast pipe sections.

Apertured lugs, as indicated at 26 and 27 project outwardly from the tube 16 at substantially diametrically opposite locations around the tube and near the larger end of the tube, these lugs being disposed adjacent the upper edge of the bottom reinforcing band 19, as is clearly illustrated in Figures 2 and 3.

Hooks 28 and 29 are pivotally connected intermediate their lengths to the lugs 26 and 27, respectively, and extend longitudinally of the tube 16. The lugs are preferably provided in pairs of spaced apart lugs and each hook is disposed between the lugs of one pair, the lugs of each pair having registering apertures therein, and pivot pins 30 and 31 extend through the apertured lugs and through registering apertures in the hooks 28 and 29 respectively to pivotally connect the hooks to the tube 16 for movement about axes which are slightly spaced from but are generally tangent to the outer surface of the tube.

At their ends adjacent the larger or lower end of the tube the hooks are provided with notches, as indicated at 32, for the hook 29, which notches provide hook formations at these ends of the hooks engageable with the rim of the pallet ring 12 to releasably lock the pallet ring to the tube 16 at the larger, lower end of the latter.

Compression springs 32 and 34 are disposed between the tube 16 and the ends of the hooks 28 and 29 respectively, remote from the hook formations thereon and these springs resiliently urge the hook formations of the hooks inwardly of the tube and into locking engagement with the rim of the pallet ring 12. The bottom reinforcing ring 19 and the tube are provided with apertures, as indicated at 34, through which the ends of the hooks having the hook formations extend and reinforcing plates 35 and 36 are mounted on the outer surface of the tube and interposed between the tube and the adjacent ends of the spring 32 and 33.

A bail 37 extends between the hooks 28 and 29 and the tube 16 at the under side of the lugs 26 and 27 and is pivotally secured at its ends to the bottom reinforcing ring 19, as indicated at 38 and 39, for rocking movement about axes disposed substantially radially of the tube and including an angle of approximately 90° therebetween. This bail bears against the inner edges of the hooks between the lugs 26 and 27 and the lower ends of the hooks, the inner edge portions of the hooks at the location thereof engaged by the bail being curved inwardly of the tube, as is particularly illustrated in Figure 2. With this arrangement, when the free intermediate portion of the bail is forced downwardly as by foot pressure of the operator, the ends of the hooks engaging the pallet ring 12 are forced outwardly against the force of springs 32 and 33 to release the pallet ring from the outer mould jacket so

that the outer jacket can be lifted off of the pipe section casting therein.

In using the apparatus, the pallet ring is first assembled with the core 10 and base plate 11 and supported on the blocks 13 surrounding the bottom end of the core. The jacket 15 is then assembled with core and the pallet ring so that the pallet ring is received in the lower, larger end of the jacket and the jacket is uniformly spaced from the core. The concrete to form the pipe section is then packed or tamped into the annular space between the core and the jacket by a suitable mechanism well known to the art, the hooks 28 and 29 at this time engaging the rim of the pallet ring to lock the jacket and pallet ring together. As soon as the casting has hardened sufficiently the core is withdrawn leaving the jacket and pallet ring locked together and in place on the casting. The casting with the pallet ring and jacket is then moved to the curing room and the jacket is then lifted off of the casting after first releasing the hooks from the pallet ring, in the manner indicated above. The casting is then left standing on the pallet ring until a predetermined cure of the concrete casting has been obtained at which time the pallet ring is removed and returned to use with the packing or tamping machine.

It will be noted that the jacket assembly of the present invention is of minimum weight and maximum strength because of its unitary construction and that it can be easily removed from the casting upon freeing it from the pilot ring at the bottom of the casting.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A jacket assembly for casting concrete pipe sections comprising a metal tube of cylindrical shape, reinforcing bands surrounding said tube one at each end thereof, outwardly projecting handles secured to said tube intermediate the length thereof, and manually operable means carried by said tube at one end thereof for releasably locking a pallet ring in said one end of the tube, said tube being slightly tapered from said one to the other end thereof to provide draft for facilitating longitudinal separation of said tube from a concrete pipe section cast therein, and said manually operable means including hooks pivotally mounted on said tube near said one end of the latter and extending through apertures in said tube and the adjacent reinforcing band to engage the rim of a pallet ring disposed within said one end of the tube, springs interposed between said tube and said hooks resiliently urging the latter in a pallet ring engaging direction, and a foot operated element pivotally mounted on said tube and engaging said hooks to move the latter in a pallet ring releasing direction when said foot operated element is depressed by foot pressure thereon.

2. A jacket assembly for casting concrete pipe sections comprising a tube of substantially cylindrical shape adapted to be disposed in upright position, a core disposed in said tube and extending longitudinally thereof in circumferentially

spaced relationship thereto, a pallet ring disposed in the lower end of said tube in surrounding relationship to the adjacent end of said core, and manual operable means carried by said tube at a lower end thereof for releasably locking said pallet ring in said lower end of the tube, said manually operable means including hooks pivotally mounted on said tube near the lower end of the latter and extending through apertures in said tube to engage the rim of said pallet ring, springs interposed between said tube and said hooks resiliently urging the latter into the pallet

engaging direction, and a foot operated element pivotally mounted on the tube and engaging said hooks to move the latter in a pallet ring releasing direction when said foot operated element is depressed by foot pressure thereon.
